EXPANSIBLE DRILL BIT

Archer W. Kammerer, Fullerton, Calif.

Application August 12, 1948, Serial No. 43,789

17 Claims. (Cl. 255—78)

1

This invention relates to drill bits, and more particularly to rotary bits of the expandable type for drilling or reaming holes below well casing, or other well conduits, greater in diameter than the inside diameter of the casing through which the bits are capable of passing.

This application is a continuation-in-part of my applications for "Rotary Drill Bits," Serial No. 597,744, filed June 6, 1945, which issued as Patent No. 2,466,991, and "Expandable Rotary Drill Bits," Serial No. 686,806, filed July 29, 1946, and "Expandable Rotary Drill Bit and Method of Assembling the Same," Serial No. 779,592, filed October 13, 1947.

An object of the present invention is to provide an expandable drill bit embodying improved means for releasably holding the cutters of the bit initially in retracted position.

A further object of the invention is to provide an expandable drill bit embodying a positive acting, hydraulically releasable device for initially holding three or more angularly spaced cutters in retracted position. In this connection, the device is also applicable for holding one or two cutters in retracted position.

Another object of the invention is to provide an improved lock device in a rotary expandable drill bit for holding cutters positively in the outward position to which they have been previously expanded.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a side elevation of a drill bit embodying the invention;

Fig. 2 is a cross-section taken along the line 2—2 on Fig. 1;

Fig. 3 is an enlarged partial longitudinal section taken along the line 3—3 on Fig. 2, with the cutters locked in retracted position;

Fig. 4 is a view similar to Fig. 3, with the cutters released and locked in expanded position; and

Figs. 5, 6 and 7 are cross-sections taken along the lines 5—5, 6—6 and 7—7, respectively, of Fig. 4.

As shown in the drawing, the rotary drill bit

2

A is attached to a string of drill pipe B, by means of which it is lowered through a well casing C in a well bore to a point below the casing shoe D at which enlargement of the bore hole is to commence. The drill bit preferably has a pilot bit 10 at its lower end for centering the bit in a hole that may have already been drilled, or for drilling the central portion of new hole in the absence of pre-existing hole. The main portion of the bit is capable of enlarging the bore hole by producing and operating upon a formation shoulder E, as hereinafter described.

The upper end of the bit consists of a driving mandrel 11, whose upper pin 12 is threadedly connected to a sub 13 forming the lower end of the drill pipe string B. This mandrel includes an upper kelly or drill stem member 14 slidably splined to the main body 15 of the bit. As disclosed in the drawings, the exterior 14a of the kelly is hexagonal in shape, and is telescopically received in a companion hexagonal socket 15a within the body. The mandrel has a limited range of longitudinal movement within the body, its upward movement being limited by engagement of an external shoulder 16 on the kelly with a retainer ring 17 at the upper end of the body, suitably secured thereto, as by the use of welding material 18.

The body 15 has a plurality of expandable parts 30 mounted on it, comprising cutter supporting members 19 pivotally mounted in body slots 20 on pivot or hinge pins 21 suitably secured to the body, as by the use of welding material 22. Each cutter supporting member consists of a depending leg 23, having a bearing supporting pin 24 inclined inwardly and downwardly, and on which a roller side cutter 25 is rotatably mounted. Anti-friction roller and ball bearing elements 26, 27 are preferably placed between each cutter 25 and bearing pin 24, the roller bearing 26 transmitting radial thrusts and the ball bearings 27 both radial and axial thrusts. The ball bearings 27 also retain each cutter on a pin, being inserted in place through a passage 28 in the bearing supports, which is then closed by a plug 29 welded to the pin 24. The plug or pin 29 depends from the passage 28 and is used to hold the cutters 25 in retracted position, as pointed out below.

Each cutter supporting member 19 also includes an upwardly extending arm 30, against which an elastic expander 31 bears. This expander, in the form of a compressed coil spring, is received within a retainer pocket 32 in the body 15, and exerts its force against the arm 30, tending to swing it inwardly and thus urge the cutter 25 on the other side of the fulcrum pin 21 in an outward direction. The extent of this

outward movement is limited by engagement of stop shoulders 33, 33 on opposite sides of the cutter supporting member 19 with cooperable body stop shoulders 34, 34.

After the cutters 25 have been expanded outwardly by the expander springs 31 to the maximum extent, they can be locked in this position by a tubular member 35 of the mandrel 11, which is piloted in the kelly 14. This member is provided with a lock portion 47, movable from an upper position in transverse alignment with inner supporting member recesses 36, permitting retraction of the cutters, to a lower position opposite lugs 37 formed on and projecting inwardly from the supporting member legs 23, preventing retraction of the cutters.

The tubular member 35 is connected in swivel fashion to the kelly 14, to permit relative arcuate or rotary movement therebetween, which can occur to a slight extent. However, the kelly and tubular member are coupled together for longitudinal movement in both directions. This is accomplished by providing an anti-friction thrust bearing between a boss or shoulder 39 on the tubular member and the kelly 14. The shoulder 39 is received within a lower socket 14b in the kelly and has a toroidal raceway 70 on its exterior, around which a plurality of bearing balls 71 can ride. These balls are also received in an opposed toroidal raceway 72 in the kelly.

The balls 71 are insertable into the raceways through a hole or passage 13 extending through the external shoulder 16 on the kelly and communicating with its internal race 72. After the balls have thus been disposed in position, the hole is closed by a suitable pin or plug 74, which is prevented from moving outwardly of the kelly by the inner wall of the surrounding body 15.

The tubular member 35 has an upper portion 35a extending into the central bore 14d of the kelly, with the upper terminus 15 of the member 35a flaring upwardly and outwardly, to guide a ball 76, or corresponding element, into the central passage 35e through the tubular member 35. Fluid pumped down the drill string B will flow through the kelly pin 12 and into the central passage 35e. It is prevented from flowing around the exterior of the tubular member 35 by a suitable packing 77 disposed between the upper portion 35a of the tubular member and the kelly adjacent the upper end of the tubular member shoulder 39.

The arrangement between the tubular member 35 and kelly 14 is such that both downward and upward movement is transmitted between the kelly 14 and tubular member 35 from one raceway 70 or 72, through the ball bearing elements 71, to the other raceway 72 or 70. In this manner, the kelly 14 and tubular member 35 are caused to move jointly in both longitudinal directions, but they are free to partake freely of relative movement therebetween.

The mandrel 11 is normally held in its upper position with respect to the main body 15 of the bit and the supporting members 19 by a helical retractor spring 38 encircling the tubular member 35, with its upper end engaging the mandrel shoulder 39 and its lower end engaging a spring seat 40 at the lower end of the hexagonal body socket 15a. This spring seat 40 also serves as an upper bearing guide for the tubular mandrel member 35, whose lower end is slidably within a lower bearing guide 41 below the lugs 37, which is integral with or secured to the main body of the bit. The two guides 40, 41 form a spaced two-

point support for the mandrel member 35 and assist it in resisting inward movement of the cutter legs 23 to retracted position during the reaming or cutting operation.

5 Circulating fluid can pass downwardly through the string of drill pipe B and through the tubular mandrel 11 for ejection from its lower discharge nozzle 35c and onto the cutters 25, to cleanse them of cuttings and flush the latter from the drilling area to the top of the well bore. This circulating fluid is also availed of to unlatch the cutter supporting members 19, in the event it is desired to hold them positively in retracted position.

15 The cutters may be retained initially in retracted positions against the expansive forces of the springs 31 by means of a trip device. This device includes a holding plate or member 78 secured to the lower end of a central rod 79, whose upper end projects into the tubular member passage 35e. A head 80 is secured to the upper end of the rod, which has peripheral notches 81 therein, in order to allow fluids to pass upwardly into the central passage 35e and into the drill string B. The holding member 78 has spaced holes 82 in its outer portion for receiving the lower ends 29a of the ball bearing plug or pins 29.

20 When the holding device 78 is disposed over the pins 29, the cutter supporting members 19 are prevented from expanding under the influence of the springs 31, thereby holding the cutters 25 in retracted position. It is to be noted that the pins 29 are inclined initially in a downward and outward direction, so as to prevent the holding member 78 and the rod 79 connected thereto from moving downwardly until purposely released, which downward movement would allow outward expansion of the cutters 25. Such release can occur as a result of fluid pressure acting downwardly on the ball 76, which can 25 rest on the head 80.

30 During lowering of the cutting tool to the point at which the reaming operation is to begin, the holding device 78, 79 retains the cutters 25 in retracted position. During this lowering operation, fluid may flow upwardly around the holding device rod 79 and through the notches or recesses 81 in the head 80 into the tubular member passage 35e. The fluid lifts the ball 76 upwardly with it, as limited by a screen 83 secured to the upper end of the pin 12 by screws 84, and then continues its upward flowing to fill the tubular drill string B with the drilling fluid.

35 When the point in the well bore has been reached at which the reaming operation is to begin, the pumps at the top of the well bore are started and drilling fluid pumped down the drill string B. The ball is then forced down through the passage 35e onto the head 80. Since the diameter of the ball is preferably equal to the 40 diameter of passage 35e, it substantially closes the passage 35e to downward flow of fluids, which allows the pumps at the top of the well bore to exert a pressure on the fluid in the drill string B and tubular member 35. This pressure acts 45 downwardly on the ball 76, which correspondingly exerts a downward force on the holding device 79, 78, shifting the latter in a downward direction off the pins 29, and the ball 76 and rod 79 completely out of the passage 35e. The pins 29 are 50 thereby released, allowing the springs 31 to expand the cutters 25 outwardly, while at the same time the passage 35e is free from restrictions, which allows fluid to be pumped through its lower nozzle 35c onto the cutters.

55 The cutters may also be held in retracted po-

sition by a band 85, which encompasses the legs 23 and holds them inwardly against the force of the springs 31. This band may be formed of metal box strapping that is readily breakable, its ends being held together by a clip 86, in a manner well known to warehousemen. A jarring action, such as that incident to rotation of the bit, is sufficient to break or snap the strap 85, which is thus released from the legs 23.

If desired, the band 85 may be used to hold the 10 cutters 25 retracted in lieu of the trip device 78, 79.

In the operation of the device the tool A is mounted on the lower end of the drill string B, with its parts held in retracted position by the latch or trip device 78, 79, and also, if desired, by the strap 85, as shown in Fig. 3. In this position of operation, the compressed retractor spring 38 holds the mandrel 11 and its kelly 14 in an upward position with respect to the body 15, as determined by engagement of the kelly shoulder 16 with the body retainer ring 17. With the mandrel in this position, its lock portion 47 is elevated above the lugs 37 on the cutter supporting members 19, being received within the inner recesses 36 in the supporting members, which permits the latter to be held inwardly against the action of the expander springs 31.

The tool is lowered through the well casing C, and upon reaching the position in the well bore below the casing shoe D at which the drilling operation is to begin, the pumps are started at the surface of the well bore, the fluid under pressure in the drill string and bit A forcing the trip device 78 off the pins 29, releasing the cutting supporting members 19 for outward expansion under the influence of the springs 31. If the band or strap 85 is used, rotation of the bit by the drill pipe B will break the band and release the cutter supporting members 19.

The drill string B is then rotated to rotate the main bit body 15 through the splined kelly and body connection 14a, 15a, the expander springs 31 forcing the arms 30 inwardly and the cutters 25 outwardly against the formation. Rotation is continued without moving the drill string longitudinally until the side cutters 25 enlarge the diameter of the hole to the maximum extent, as determined by the eventual abutting of the supporting member stop shoulders 33 with the companion body stop shoulders 34. Thereafter, the drill string is lowered to cause the formation shoulder E, produced in the well bore by the cutters 25 under the action of the expander springs 31, to support the cutter members 19 and body 15, and prevent their downward movement.

Since the body 15 cannot move downwardly, drilling weight imposed on the drilling string B shifts its connected mandrel 11 downwardly within the body 15 against the action of the retractor spring 38 until the lower end 48 of the kelly 14 engages the upper spring seat and guide 40. This downward movement also shifts the tubular member 35 downwardly, because of the interlocking ball thrust bearing 70, 71, 72, to position the mandrel or tubular member lock portion 47 opposite and in alignment with the lugs 37 on the inner portions of the cutter supporting members 19, providing a positive lock by preventing inward movement of the cutters. So long as down weight is imposed on the drill string B, and the cutters 25 rest on the formation shoulder E, the cutters are prevented from moving inwardly by engagement of their lugs 37 with the mandrel lock portion 47. It is also to be 75

noted that further outward movement of the cutters beyond the predetermined maximum reaming diameter is prevented by contact between the supporting member shoulders 33 and the body shoulders 34, through which the drilling weight is transmitted to the roller cutters 25, thus relieving the hinge pins 21 of this load.

Drilling is continued by rotating the drill bit and imposing the proper drilling weight on the cutters to cause their removal of the formation material and reaming of the hole in a downward direction for the desired extent or length. When the drill bit is to be retracted and removed to the top of the well bore, all that need be done is elevate the drill string B, which moves the side cutters 25 above the formation shoulder E, and permits the retractor spring 38 to press downwardly on the body 15 and move it, together with the cutter supporting members 19, downwardly with respect to the mandrel 11. This action repositions the mandrel lock portion 47 opposite the supporting member recesses 36 and above their lugs 37, because of the ball bearing coupling 71, permitting inward swinging of the cutters 25 and their supporting members 19 when the tool passes back into the casing C, upon elevation of the drill string. The cutters 25 and their supporting members 19 will ride the wall of the casing C during elevation of the string until the tool is removed from the top of the well bore.

The lock portion 47 of the tubular member preferably has flat faces 47a engaging corresponding flat faces 37a on the lugs 37 extending inwardly from the cutter supporting members. These flat faces are preferred, to present a surface contact between the members, and thus increase the load carrying capacity of the lock device, enabling it to resist to a greater extent the reactive force of the formation tending to press the cutters 25 inwardly from their expanded positions. The remaining portions of the tubular members 35, namely, the shoulder 39, the upper section 35a above the shoulder, and the portions 45 which ride in the upper and lower bearing guides 40, 41 are all circular in cross-section to permit relative rotation, even to a slight extent, between the tubular member 35 and the kelly 14 within which it is received.

The relative rotation of the tubular member 35 and its locking portion 47 with respect to the driving kelly 14 is important, since it permits the lock portion 47 to adjust itself with respect to the lugs 37 on the cutter supports 19 and thus insures a surface contact therebetween. There is a slight play of the supporting members 19 on their hinge pins 21, permitting a slight angular adjustment of the supporting member about a longitudinal axis with respect to the expander portion 47. In the event that an error has been made in the mounting of the pin 21 in the body 15, the supporting member 19 may pivot slightly about the longitudinal axis, and this pivoting action, coupled with the swivel arrangement of the tubular member 35 and lock portion 47 with respect to the kelly 14 (which permits the tubular member 35 to rock or move about the body axis), offers assurance that the contact between the lock portion 47, 47a and the lugs 37, 37a will be a surface contact. The swivel action of the tubular member 35 in the kelly 14 is facilitated and is kept free by the ball bearings 71.

The inability of the tubular member 35 to swivel or move about the bit axis might merely result in a line contact between the cutter lugs

37 and the lock portion 47 of the tubular member, thus producing concentrated wear along both of these parts during their resistance to the formation reactive forces tending to press the cutters 25 inwardly from their retracted positions. Such wear would permit the cutters to shift inwardly, and would result in the production of a reamed hole of lesser diameter than the diameter desired.

There is still a further advantage to the swivel or relatively oscillatable connection between the tubular lock member 35 and the driving kelly 14. Although the kelly is telescopically splined to the body 15, a slight amount of relative arcuate movement between them is permitted, because of the working clearances that must be maintained between the hexagonal kelly 14a and hexagonal socket 15a in the body. The rigid attachment of the tubular lock member 35 to the kelly 14 would result in angularly moving the lock portion 47 with respect to the cutter supports 19 during the drilling operation, and would result in point contact between the lock portion 47 and lugs 37, rather than the desirable surface contact. The swivel connection prevents the transmission of such relative angular movement of the kelly 14 with respect to the body 15 to the tubular member 35, since the latter is free and is unaffected by the turning movement of the kelly. The drilling torque transmitted through the driving kelly 14 to the body 15 need not pass through the tubular member 35 and its locking portion 47 onto the supporting members 19.

It is, accordingly, apparent that an expandable rotary drill bit has been provided, in which assurance is had that the cutters will be held retracted in a positive manner during lowering of the bit through the well casing and well bore to the desired point at which the hole enlarging operation is to commence. Thereafter, the holding device is removed by positive hydraulically operable means, which, nevertheless, does not interfere with automatic filling of the drill string with the well fluid as the bit is lowered in the well bore. The hydraulic lock arrangement is such as to enable more than two cutters (such as the three cutters disposed 120 degrees apart) to be held positively in retracted position. The use of three or more cutters insures appropriate centering of the bit in the well bore, and its production of an enlarged hole circular in cross-section. In addition, assurance is had that the lock device may accommodate itself readily, to provide the proper contact between the lock portion 47 and the lugs 37 on the cutter supporting members.

The inventor claims:

1. In a rotary drill bit: a main body having a fluid passage; cutter means carried by said body for lateral movement with respect to said body; means engaging said cutter means for expanding said cutter means laterally outward; and latch means connected to said cutter means and extending into said passage, and releasable by the pressure of fluid in said passage, for holding said cutter means in an inward position.

2. In a rotary drill bit: a main body having a fluid passage; cutter means carried by said body for lateral movement with respect to said body; means engaging said cutter means for expanding said cutter means laterally outward; latch means connected to said cutter means and extending into said fluid passage for releasably holding said cutter means in retracted position; and means in said passage for releasing said latch means from said cutter means.

3. In a rotary drill bit: a main body for lateral movement with respect to said body having a fluid passage; cutter means carried by said body; means engaging said cutter means for expanding said cutter means laterally outward; latch means connected to said cutter means and extending into said fluid passage for releasably holding said cutter means in retracted position; and a ball movable in said passage into engagement with said latch means for enabling fluid under pressure in said passage to release said latch means from said cutter means.

4. In a rotary drill bit: a main body having a fluid passage; cutter means carried by said body for lateral movement with respect to said body; means engaging said cutter means for expanding said cutter means laterally outward; and latch means connected to said cutter means and for releasably holding said cutter means in an inward position, and instrumentalities movable within said passage engageable with said latch means to release said latch means from holding said cutter means in such inward position.

5. In a rotary drill bit: a main body; cutter means mounted on said body for lateral movement with respect to said body; spring means engaging said cutter means for expanding said cutter means laterally outward; a mandrel having a fluid passage and adapted to be connected to a tubular drill string, said mandrel being slidably splined to said body and movable in one longitudinal direction along said body to a position preventing inward movement of said cutter means from its outwardly expanded position; and hydraulically operable latch means extending into said fluid passage and connected to said cutter means for releasably holding said cutter means in an inward position against the action of said spring means.

6. In a rotary drill bit: a main body; cutter means mounted on said body for lateral movement with respect to said body; spring means engaging said cutter means for expanding said cutter means laterally outward; a mandrel having a fluid passage and adapted to be connected to a tubular drill string, said mandrel being slidably splined to said body and movable in one longitudinal direction along said body to a position preventing inward movement of said cutter means from its outwardly expanded position; releasable latch means connected to said cutter means and extending into said fluid passage for holding said cutter means in retracted position against the action of said spring means; and a ball movable in said passage into engagement with said latch means for enabling fluid pressure in said passage to release said latch means from said cutter means.

7. In a rotary drill bit: a main body; a supporting member mounted on said body for lateral movement with respect to said body; a cutter rotatable on said supporting member; rollable bearing elements between said cutter and supporting member; means for preventing removal of said elements from their bearing position between said cutter and supporting member; means engageable with said supporting member for expanding said cutter outwardly; means connected to said preventing means for holding said supporting member and cutter in retracted position and means carried by said body engageable with said holding means for releasing the same.

8. In a rotary drill bit: a main body; a supporting member mounted on said body for lateral movement with respect to said body; a cutter

rotatable on said supporting member; ball bearing elements between said cutter and supporting member; said supporting member having a hole through which said elements are insertable in their bearing position between said cutter and supporting member; means closing said hole; means connected to said hole closing means for holding said supporting member and cutter in retracted position and means carried by said body engageable with said holding means for releasing the same.

9. In a rotary drill bit: a main body having a fluid passage therein; a supporting member mounted on said body for lateral movement with respect to said body; a cutter rotatable on said supporting member; rollable bearing elements between said cutter and supporting member; means for preventing removal of said elements from their bearing position between said cutter and supporting member; means engageable with said supporting member for expanding said cutter outwardly; and latch means extending into said passage and connected to said preventing means for initially holding said supporting member and cutter in retracted position, said latch means being releasable from said preventing means by the pressure of fluid in said passage.

10. In a rotary drill bit: a main body having a fluid passage; cutter means carried by said body for lateral movement with respect to said body; means engaging said cutter means for expanding said cutter means laterally outward; latch means connected to said cutter means and extending into said passage, and releasable by the pressure of fluid in said passage, for initially holding said cutter means in an inward position; and a readily breakable band encompassing said cutter means to hold said cutter means in retracted position.

11. In a rotary drill bit: a body; cutter means mounted on said body for lateral movement with respect to said body; means for expanding and holding said cutter means laterally outward, comprising a first member connectable to a drill string and slidably splined to said body; a second member rotatable with respect to said first member and engageable with said cutter means for holding said cutter means laterally outward; and rollable elements between said first member and second member coupling said members together for joint longitudinal movement.

12. In a rotary drill bit: a body; cutter means mounted on said body for lateral movement with respect to said body; means for expanding and holding said cutter means laterally outward, comprising a first member connectable to a drill string and slidably splined to said body; a second member rotatable with respect to said first member and engageable with said cutter means for holding said cutter means laterally outward; said first member and second member having opposed raceways; and balls in said raceways coupling said members together for joint longitudinal movement.

13. In a rotary drill bit: a body; cutter means mounted on said body for lateral movement with respect to said body; means for expanding and holding said cutter means laterally outward, comprising a first member connectable to a drill string, said first member being positioned in and slidably splined to said body, a second member within said first member and engageable with said cutter means for holding said cutter means laterally outward, said first member and second member having opposed raceways; balls in said

raceways coupling said members together for joint longitudinal movement; said first member having a hole therein through which said balls are insertable in said raceways; and a plug in said hole.

14. In a rotary drill bit: a main body having a fluid passage; cutter means carried by said body for lateral movement with respect to said body; means engaging said cutter means for expanding said cutter means laterally outward; releasable latch means connected to said cutter means for holding said cutter means in an inward position, said latch means including instrumentalities extending into said passage and subject to the force of fluid in said passage to remove said instrumentalities from said passage and release said latch means from cutter means holding position.

15. In a rotary drill bit: a main body; a plurality of supporting members mounted on said body for lateral movement with respect to said body; a cutter rotatable on each of said supporting members; a set of rollable bearing elements between each of said cutters and companion supporting members; individual means for preventing removal of each set of elements from their bearing position between an associated cutter and supporting member; means engageable with said supporting means for expanding said cutters outwardly; means interconnecting said individual preventing means for releasably holding said supporting members and cutters in retracted position and means carried by said body engageable with said holding means for releasing the same.

16. In a rotary drill bit as defined in claim 13, said plug being engageable with said body for preventing removal of said plug from said hole.

17. In a rotary drill bit: a main body having a fluid passage; a plurality of supporting members mounted on said body for lateral movement with respect to said body; a cutter rotatable on each of said supporting members; a set of rollable bearing elements between each of said cutters and companion supporting members; individual means for preventing removal of each set of elements from their bearing position between an associated cutter and supporting member; means engageable with said supporting means for expanding said cutters outwardly; means interconnecting said individual preventing means for releasably holding said supporting members and cutters in retracted position; and means extending into said passage and subject to the force of fluid in said passage for releasing said interconnecting means from holding said supporting members and cutters in retracted position.
